UNITED STATES PATENT OFFICE.

CHARLES H. STRANGE, OF MINERSVILLE, PENNSYLVANIA.

MINING SELF-LOADING AND UNLOADING SCRAPER.

1,397,560.

Specification of Letters Patent.

Patented Nov. 22, 1921.

Application filed June 29, 1920. Serial No. 392,862.

To all whom it may concern:

Be it known that I, CHARLES H. STRANGE, a citizen of the United States, residing at Minersville, in the county of Schuylkill and

5 State of Pennsylvania, have invented a new and useful Improvement in Mining Self-Loading and Unloading Scrapers, of which the following is a specification.

This invention relates to apparatus which 10 is employed in mines for transferring material blasted from the working faces in the chambers to the cars in the entries, and more particularly to those scoop buckets which are especially adapted to be drawn by ropes 15 into and out of thin vein cuttings in coal mines, but which, of course, are workable in seams of practically any height and for removing other minerals or metals than coal from the mine to the car or from one place 20 to another.

The object of the invention is to provide a scoop bucket for such purposes which can be manipulated by simple apparatus with a minimum expenditure of labor, power and 25 time, so as to enter the chamber, scoop up a maximum quantity of material, withdraw from the chamber and deposit its load in the mine car located in the entry opposite the chute.

30 This object is attained by hinging the back of the bucket at its lower edge and connecting the swinging edge of the back with both the tail rope that is used to draw the empty bucket into the chamber and with the 35 head rope that is used to pull the loaded bucket out of the chamber, in such manner that the draft of the tail rope first opens down the back and then pulls the bucket along and causes the lowered back to dig 40 into and scoop up the material blasted from the working face of the chamber, and the draft of the head rope first closes up the back and then pulls the bucket with its load from the chamber, this arrangement enabling the bucket to be drawn straight in 45 and straight out without any turn, thereby insuring the return of the bucket with a full load in the shortest path and quickest possible time.

50 In the accompanying drawings Figure 1 shows a plan of an entry, chute and chamber of a coal mine illustrating the apparatus used and the method of operating the improved scoop bucket. Fig. 2 shows a plan of 55 the bucket. Fig. 3 shows a longitudinal section of the bucket. Fig. 4 shows a side view

of the bucket being drawn into the chamber and scooping up a quantity of coal from the bottom with its lowered back. Fig. 5 is a similar view showing the back of the bucket 60 nearly closed by the pull of the head rope. Fig. 6 shows the back completely closed and the bucket with its load ready to be drawn out from the chamber.

The bucket is formed of two vertical or 65 substantially vertical and parallel side plates 1 of steel or iron that are connected across the top near the head end by a cross brace or arch 2 desirably formed from angle iron. Attached to the outside of the side walls near 70 the head end are runner bars 3 which serve to strengthen the plates and guide the bucket. The side plates near the tail end are connected across the top by a cross brace or arch 4 desirably formed from angle iron. 75 The back 5 of the bucket shown, which has side walls 6, is connected to the side plates near the bottom by hinge bolts 7. A rib 8 is secured to the back approximately midway between the sides. The front and bottom of the bucket are open.

A bridle chain 9 is connected by clevises 10 with the side plates near the head end, and this bridle is provided with an eye 11 into which is connected the end of the head 85 rope 12 that is used to draw the bucket and its load from the chamber. The tail rope 13 for drawing the empty bucket into the chamber is fastened to a clevis 14 attached to the rib 8 at the free end of the back. A steel 90 rope 15 is attached by a clevis 16 to the swinging end of the back and a chain 17 is attached to the bridle eye 11, the rope passing over a pulley 18 mounted in a block on the cross brace 4 and being connected with 95 the chain by a turn buckle 19. The length of this connection between the back and bridle eye is such that when the bridle is slackened the back may be opened down but when the bridle is drawn taut the back is 100 pulled up and closed.

When a bucket is to be used its head rope is passed around a snatch-block 20 attached to a prop placed in the entry 21 opposite the chute or neck 22 from the chamber 23, and 105 is wound on the drum 24 of a hoist mounted on a locomotive 25 which travels on rails 26 laid in the entry. The tail rope is run around a snatch-block 27 fastened to a prop located as near the face of the chamber 110 as feasible, around a snatch-block 28 attached to a prop near one side of the chani-

ber a little distance from the face and around a snatch-block 29 secured to a prop at one side of the mouth of the chute, and its end is fastened to a hoisting drum 30 on the 5 locomotive. To bring out coal the head rope is slackened and the hoist started so as to wind the tail rope on the drum 30. This opens the back and draws the bucket with the back down along the floor of the chamber until it enters and becomes filled with 10 loose coal which has been blasted from the face of the chamber. When the bucket is full the tail rope drum is released so the tail rope can unwind and the hoist started so 15 as to wind the head rope on the drum 24. The pull of the head rope first closes up the back and then when the back is closed continued pull on the head rope draws the bucket with the load it has scooped up along 20 the chamber to the chute until the bucket passes over the apron 31 and deposits its load in the car 32 which is standing on the track below the apron. To facilitate the 25 passage of the bucket, guiding planks 33 are secured to props 34 arranged at suitable intervals along the chamber and chute from near the working face to the platform. After the coal has been removed from one 30 locality the prop near the face of the working, supporting the snatch-block around which the tail rope passes, may be moved to another position or, what is preferred, a second prop with snatch-block 35 may be set in a different locality so that the tail 35 rope need only be transferred from one snatch-block to the other in order to cause the bucket to enter the pile of coal that is left. With this apparatus the bucket passes in a straight line in and out of the chamber 40 and the back is automatically opened without loss of time so that it will scoop up its load of coal, and is automatically closed without loss of time so that it will keep the load in the bucket when it is drawn out.

45 The invention claimed is:—

1. A scraper for transferring coal detached from a vein from the working face of a chamber to a car in the entry of a mine, said scraper having an open top, open bottom and open front end and comprising substantially vertical side plates, transversely extending arches connecting the side plates, a transversely extending back plate hinged at its lower edge to the lower edges of the side plates, means for the connection of the head rope to the side plates, means for the connection of a tail rope to the back plate, and a flexible connection between said head and tail rope connection means.
- 60 2. A scraper for transferring coal detached from a vein from the working face of a chamber to a car in the entry of a mine, said scraper having an open top, open bot-

tom and open front end and comprising substantially vertical and parallel side plates, 65 cross braces connecting the tops of said side plates, a transversely extending back plate hinged at its lower edge to the side plates, a rib extending longitudinally along the inside of the center of the back plate, a 70 bridle for the connection of a head rope attached to the side plates, means for the connection of a tail rope to said rib, and a flexible connection between said bridle and rib.

3. A scraper for transferring coal detached from a vein from the working face of a chamber to a car in the entry of a mine, said scraper having an open top, open bottom and open front end and comprising substantially vertical and parallel side plates, 75 a transversely extending back plate with side walls at its ends hinged at its lower edge to the back end of the side plates, means connected with the back plate for opening said plate downward and drawing the 80 scraper backward and means connected with the back plate for closing said plate upward and drawing the scraper forward.

4. A conveyer for transferring coal detached from a vein from the working face of 90 a chamber to a car in the entry of a mine comprising a scraper having an open top, open bottom and open front end and consisting of substantially vertical and parallel side plates, a plate extending transversely 95 of the side plates at the rear ends thereof and hinged at its lower edge thereto, means connected with the back plate for opening it downward and drawing the scraper backward in a straight line to the working face 100 of the chamber, and means for closing up the back plate and drawing the scraper forward in a straight line over a car in the entry.

5. An apparatus for conveying coal detached from a vein from the working face 105 of a chamber to a car in the entry of a mine comprising a scraper having an open top, open bottom and open front end and consisting of substantially vertical and parallel side 110 plates and a plate hinged at its lower edge and adapted to be opened from and closed against the rear ends of the side plates, a tail rope connected with the back plate for swinging down the back plate and drawing 115 the scraper in a straight line from the entry to the working face of the chamber, a head rope connected with the side plates and back plate for swinging up the back plate and drawing the scraper forward in a straight 120 line from the working face over a car in the entry of the mine, a locomotive and a hoist having a drum for winding up the head rope and a drum for winding up the tail rope mounted on the locomotive.

CHARLES H. STRANGE.
